UNITED STATES PATENT OFFICE.

WILLIAM F. HATCH, OF MILWAUKEE, WISCONSIN, ASSIGNOR TO THE PALMOLIVE COMPANY, OF MILWAUKEE, WISCONSIN, A CORPORATION OF WISCONSIN.

DESIGN FOR A SOAP-DISPENSER.

51,691.

Specification for Design.

Patented Jan. 15, 1918.

Application filed November 5, 1917. Serial No. 200,447. Term of patent 14 years.

To all whom it may concern:

Be it known that I, WILLIAM F. HATCH, a citizen of the United States, residing at Milwaukee, in the county of Milwaukee and State of Wisconsin, have invented a new, original, and ornamental Design for a Soap-Dispenser, of which the following is a description, reference being had to the accompanying drawing, forming part thereof.

The figure is a perspective view of a soap dispenser showing my new design.

I claim:

The ornamental design for a soap dispenser, as shown.

WILLIAM F. HATCH.

Witnesses:

F. G. NETZHAMMER,
J. E. KRASEMAN.
